OLEFIN SEPARATION WITH A TETRAALKYL UREA

Earle C. Makin, Jr., El Dorado, Ark., assignor to Monsanto Chemical Company, St. Louis, Mo., a corporation of Delaware

No Drawing. Filed Oct. 15, 1958, Ser. No. 767,266

12 Claims. (Cl. 183—115)

This invention relates to the separation of mixtures of hydrocarbons and more particularly to the separation of mixtures of aliphatic hydrocarbons containing less than six carbon atoms.

Many refinery operations result in the production of a mixture of aliphatic hydrocarbons containing less than six carbon atoms and composed of paraffins and olefins, either mono- or diolefins. The olefinic component of such streams is most useful in the preparation of polymeric materials. Frequently, the olefinic component of such streams can be used without complete separation from the paraffinic components if its concentration can be raised to a suitable level.

It is an object of this invention to provide an improved method for concentrating the olefinic content of hydrocarbon streams composed of mixtures of paraffins and olefins containing less than six carbon atoms. Additional objects will become apparent from the description of the invention.

It has now been discovered that the olefinic content of a hydrocarbon stream comprising a mixture of paraffins and olefins containing less than six carbon atoms can be increased through the selective solvent action of tetraalkyl ureas. Specifically, this invention comprises contacting a feed mixture of aliphatic hydrocarbons containing paraffins and olefins each containing less than six carbon atoms with a tetraalkyl urea and recovering from said tetraalkyl urea a hydrocarbon mixture having a higher olefin content than said feed mixture.

The tetraalkyl ureas have been found to have a remarkable selective solvency for mono-olefins and diolefins containing less than six carbon atoms as compared with paraffins containing less than six carbon atoms. This unusual phenomenon is illustrated in Table I which sets forth the Bunsen coefficients for butadiene and butenes in several tetraalkyl ureas as compared with di-alkyl ureas. The Bunsen coefficients represent the volume of hydrocarbon dissolved per volume of solvent at 25° C. and 760 mm. Hg absolute.

Table I

Solvent	Bunsen Coefficient For—	
	Butadiene	Butenes
Tetraethyl urea.....	8.64	4.55
Tetrabutyl urea.....	9.43	4.75
1,1-Diethyl-3,3-di-isoamyl urea.....	9.09	5.20
1,1-Di-n-butyl urea.....	3.61	1.81
1,1-Diamyl urea.....	3.70	1.96

This unusual behavior of the tetraalkyl ureas permits their use in the concentration of olefins in mixtures of aliphatic hydrocarbons containing less than six carbon atoms. This utility is illustrated in the following example:

A feed gas was prepared having the following composition expressed as volume percent

		Percent
Butadiene		29.1
Butanes		50.5
Butenes		18.2
5 C ₃ aliphatics		1.9
C ₆ aliphatics		0.3

This hydrocarbon mixture was then bubbled through tetraethyl urea and tetra-n-butyl urea at a gas-to-solvent volume ratio of 40:1 at a solvent temperature of 26°—30° C. In each case the raffinate and extract phases were then analyzed for hydrocarbon content and the results are set forth in Table II.

Table II

Hydrocarbon Composition	Tetraethyl Urea		Tetra-n-butyl Urea	
	37% Raffinate ¹	63% Extract ¹	32% Raffinate	68% Extract
Butadiene.....	Percent	Percent	Percent	Percent
Butanes.....	19.9	34.0	15.8	34.3
Butenes.....	59.9	46.1	61.1	46.7
C ₃ Aliphatics.....	18.4	17.8	19.8	17.2
C ₆ Aliphatics.....	1.8	2.0	2.3	1.7
		0.1		0.1

¹ Raffinate and extract refer to volume percent distribution of the feed gas as unabsorbed and dissolved hydrocarbon, respectively.

The results set forth in this example clearly illustrate the outstanding utility of tetraalkyl ureas as a means for solvent concentration of the olefinic content of mixtures of hydrocarbons containing less than six carbon atoms. Mixtures of hydrocarbons containing six or more carbon atoms cannot be resolved through the use of these solvents for the reason that paraffinic and olefinic hydrocarbons containing six or more carbon atoms are completely miscible with the solvents.

While any tetraalkyl urea, or mixtures of tetraalkyl ureas, can be used in the process of this invention those wherein the alkyl groups each contain not more than eight carbon atoms are preferred. Tetraalkyl ureas wherein each alkyl group contain as many as 18 carbon atoms can be used if desired. Typical of the tetraalkyl ureas that can be used in the process of this invention are those set forth in Table III.

Table III

Urea	Boiling Point, °C./mm. Hg Abs.	Pour Point, °F.
Tetraethyl urea.....	205/760	-81
1,1-Diisoamyl-3,3-diethyl urea.....	134-5/4.8	-88
Tetra-n-butyl urea.....	140-5/3.1	-88
1,1-Dicyclohexyl-3,3-diethyl urea.....	90-4/1.4	-5
1,1-Diethyl-3,3-di-n-octyl urea.....	174-9/3	-80
1,1-Di-n-butyl-3,3-di-n-octyl urea.....	173-4/1	-47
1,1-Di-n-butyl-3,3-di-n-octyl urea.....	187-8/2	-81
Tetra-n-hexyl urea.....	180-1/2	-69
1,1-Dicyclohexyl-3,3-di-n-octyl urea.....	217-3/4/2	-35
1,1-Di-n-hexyl-3,3-di-n-octyl urea.....	190-8/2	-20
1,1-Di-n-butyl-3,3-di-n-octadecyl urea.....	230-57/2	-30
Tetra-2-ethylhexyl urea.....	212-15/2	-10
1,1-Di-2-ethylhexyl-3,3-di-n-octyl urea.....	209-12/2	-59
60 Tetra-n-octyl urea.....	222-28/2	+5
1,1-Di-n-dodecyl-3,3-di-n-hexyl urea.....	250-60/2	-40
1,1-Di-n-dodecyl-3,3-di-2-ethylhexyl urea.....	200-45/7	-28
1,1-Di-n-dodecyl-3,3-di-n-octyl urea.....	265-75/2	+14
1,1-Di-n-butyl-3,3-di-n-octadecyl urea.....	297-305/2	+40
1,1-Di-n-hexyl-3,3-di-n-octadecyl urea.....	290-300/2	+25
1,1-Di-n-octyl-3,3-di-n-octadecyl urea.....	305-15/2	+35

The tetraalkyl ureas can also be mixed with other solvents to effect even more specific hydrocarbon separations as may be desired under particular circumstances.

The olefin content, both mono-olefins and diolefins, of any mixture of aliphatic hydrocarbons containing less than six carbon atoms can be increased through the novel process of this invention. Such hydrocarbon mixtures

can contain paraffins containing from 1 to 5 carbon atoms, mono-olefins such as propylene, butenes, and pentenes and diolefins such as propadiene, butadienes and pentadienes. The concentration is effected by any of the conventional techniques for vapor-liquid extraction well known to those skilled in the art. Preferably, the hydrocarbon mixture in the vapor state is merely bubbled through the liquid tetraalkyl urea. The gas-to-solvent volume ratio can be varied substantially with ratios ranging from 10:1 to 60:1 being preferred. The temperature of the solvent extraction step can also be varied with temperatures ranging from 0° C. to 100° C. being applicable. The process is very conveniently carried out at approximately room temperature. The temperature, of course, will be governed to a large extent by the fluidity of the solvent at the temperature employed, the boiling point of the hydrocarbon mixture and the pressure at which the solvent extraction is carried out. Atmospheric pressure has been found to be very suitable although pressures either below or above atmospheric can be used if desired. Single or multiple stage solvent extraction can be used as desired.

The hydrocarbon mixture concentrated in the extract phase can be recovered by any method well known to those skilled in the art. A simple distillation is usually the preferred method. The hydrocarbon streams recovered from the extract phase and the raffinate phase can be further processed in any desired manner.

What is claimed is:

1. In a process for separating olefins from a feed mixture of aliphatic hydrocarbons containing paraffins and olefins each containing less than six carbon atoms, the step of extracting said mixture with a tetraalkyl urea.
2. In a process for separating olefins from a feed mixture of aliphatic hydrocarbons containing paraffins and olefins each containing less than six carbon atoms, the step of contacting said feed mixture with a tetraalkyl urea to form an extract phase and a raffinate phase and recovering from said extract phase a hydrocarbon mixture containing a higher concentration of olefins than contained in said feed mixture.
3. In a process for separating olefins from a feed mix-

ture of aliphatic hydrocarbons containing paraffins and olefins each containing less than six carbon atoms, the step of contacting said feed mixture maintained in the vapor phase with a liquid tetraalkyl urea to form an extract phase and a raffinate phase and recovering from said extract phase a hydrocarbon mixture containing a higher concentration of olefins than contained in said feed mixture.

5 4. The process as described in claim 3 wherein each alkyl group of the tetraalkyl urea contains from 1 to 18 carbon atoms.

10 5. A process as described in claim 3 wherein each alkyl group of the tetraalkyl urea contains from one to eight carbon atoms.

15 6. A process as described in claim 5 wherein the gas-to-solvent volume ratio is maintained in the range of from 10:1 to 60:1.

7. The process as described in claim 6 wherein the tetraalkyl urea is tetraethyl urea.

20 8. The process as described in claim 6 wherein the tetraalkyl urea is tetra-n-butyl urea.

9. In a process for separating butadiene from a feed mixture of aliphatic hydrocarbons containing butadiene and paraffins containing less than six carbon atoms, the 25 step of contacting said feed mixture in the vapor phase with a liquid tetraalkyl urea to form an extract phase and a raffinate phase and recovering from said extract phase a hydrocarbon mixture containing a higher concentration of butadiene than contained in said feed mixture.

30 10. A process as described in claim 9 wherein the gas-to-solvent volume ratio is maintained in the range of from 10:1 to 60:1.

11. A process as described in claim 10 wherein the tetraalkyl urea is tetraethyl urea.

35 12. A process as described in claim 10 wherein the tetraalkyl urea is tetra-n-butyl urea.
